HARRISON L. STALEY, OF MARTINSVILLE, INDIANA, ASSIGNOR TO STALEY MANUFACTURING COMPANY, OF MARTINSVILLE, INDIANA, A CORPORATION OF INDIANA.

WASHING-MACHINE GEARING.

958,189.

Specification of Letters Patent. Patented May 17, 1910.

Application filed December 27, 1909. Serial No. 534,943.

To all whom it may concern:

Be it known that I, HARRISON L. STALEY, a citizen of the United States, residing at Martinsville, in the county of Morgan and State of Indiana, have invented certain new and useful Improvements in Washing-Machine Gearing; and I do declare the following to be a full, clear, and exact description of the invention, reference being had to the accompanying drawings, and to the characters and figures of reference marked thereon, which form a part of this specification.

This invention relates to gearing for washing-machines of the type comprising tubs having hinged covers on which the rubbing apparatus is mounted, the invention having reference particularly to a balanced lever operated gearing for operating the rubbing apparatus.

The object of the invention primarily is to provide powerful and therefore easily operated gearing comprising a relatively heavy balance wheel, for the above mentioned class of washing machines, that will be adapted to be constructed and arranged so that the cover need not be burdened with excessive weight of machinery, in order to permit the cover and the rubbing apparatus to be easily tilted over on its hinges, a particular object being to provide improvements in oscillatory rotary gearing of the type shown in Letters Patent No. 903,613, granted to me November 10, 1908, or gearing in which a shaft is mounted horizontally on the cover to rotate continuously and drive a vertical shaft and rubbing apparatus mounted also on the cover to oscillate or move back and forth rotatively. The present invention being designed in detail for use particularly with the gearing shown in said Letters Patent, in order to illustrate and explain the purposes and functions of the present improvements, the gearing in said Letters Patent is briefly shown and described herein and comprises a rotative driving shaft, an agitator shaft for operating the rubbing apparatus, and a gearing connecting the driving shaft and the agitator shaft for causing the latter shaft to move back and forth rotatively or oscillate and also to advance forward rotatively at each alternate oscillation, so that when operating the driving shaft by hand, and especially by means of a powerful lever, unsteadiness of motion results with consequent

loss of energy in overcoming the vibrations, and therefore the specific purpose of the present invention is to provide improved lever gearing including a relatively heavy balance wheel whereby steady and uniform rotary movement of the driving shaft may be produced, a further object being to so construct and mount the gearing that the heavier portions thereof may be supported on the tub and be connected removably by the driving shaft mounted on the cover of the tub.

The invention consists of improved gearing comprising a prime mover and a balance wheel operated thereby adapted to be supported on the wash tub and to be connected by gearing mounted on a hinged cover of the tub; and the invention consists further in the parts and combinations and arrangements of parts as hereinafter particularly described and then pointed out in the appended claims.

Referring to the drawings, Figure 1 is a rear elevation of the washing machine provided with the improved gearing; Fig. 2, a side elevation of the machine with the cover tilted back so that parts of the gearing are disconnected from other parts thereof; Fig. 3, a fragmentary top plan of the tub and the gearing thereon; Fig. 4, a top plan of the movable part of the cover and parts of the gearing thereon; Fig. 5, a fragmentary side elevation of the tub and cover and portions of the gearing thereon; Fig. 6, a fragmentary elevation of the tub, and the frame portions of the gearing thereon; Fig. 7, a fragmentary elevation of the tub and cover on which the gearing is mounted and shown partly in section; Fig. 8, a fragmentary horizontal section of the tub and gearing thereon at the axis of the balance wheel; Fig. 9, a top plan of the principal parts of the oscillatory rotary gearing; and Fig. 10, a vertical sectional view of the oscillatory rotary gearing and housing thereof.

In the different figures of the drawings similar reference characters indicate like elements or features of construction herein referred to.

In attaining the primary object of the present invention a wash tub 1 is employed, on which is a stationary cover part 2 provided with hinges 3, 3', and a stop-block 4, a movable cover part 5 being attached to the hinges and adapted to swing upward and

back against the stop-block, the cover part 5 having an aperture 5' therein. The oscillatory gearing described in said Letters Patent No. 903,613, is inclosed in a housing comprising two similar parts arranged one upon the other, the lower part comprising a bottom 6 secured on the cover part 5 and having a journal-box 7 that extends into the aperture 5', a bowl shaped wall 8 extending upward from the bottom. The upper part comprises a wall 9 that is secured by bolts 10 to the lower part and has a top 11 that is provided with a journal-box 12 in alinement with the journal-box 7. The lower part of 15 the housing has a guide-rail 13 on the inner side thereof in inclined position, said lower part having an arm 14 thereon that is provided with a standard 15 having a foot 15' whereby it is suitably secured to the cover 20 part 5, the arm being provided with two journal-boxes 16 and 17 in which a driving shaft 18 is journaled and extends beyond the journal-boxes to rotate continuously, the inner end of the shaft having a dished long toothed pinion 19 thereon, the shaft extending through the pinion and its end constituting a guide-pin 20. The upper part of 25 the housing has a guide-rail 21 on its inner side and opposite to the guide-rail 13. A shaft 22 is mounted vertically in the journal-boxes 7 and 12 to rotate therein and extends into the tub, the shaft having a hub 23 thereon that is provided with ribs 24 and a collar 25 at the lower end of the hub, there 30 being a rubbing plate 26 mounted on the hub, so as to move vertically thereon and be rotated thereby, the plate having a suitable number of projections 27 thereon to turn the articles that are to be washed in 35 the tub. A conical guide 28 is attached to the shaft 22, and a combined conical guide and gear wheel 29 is secured also to the shaft and has peripheral notches so that relatively thick gear teeth 30 are provided for actuating 40 the agitator shaft or driven shaft 22. A rolling gear segment comprises a circular plate 31 having a rim 32 thereon and a central guide opening 33 through which the shaft 22 extends, there being a suitable number 45 of gear teeth 34 on the rib 32, the teeth being arranged in a circle of greater diameter than the pitch-line of the teeth 30. A suitable number of pin teeth 35 extend radially from the rim 32 and have a guide-rail 36 on their ends. The plate 31 is arranged 50 between the conical guides 28 and 29 and may roll thereon while the teeth 35 are in engagement with the pinion 19, alternately above and below the pinion. An arm 37 extends from the plate 31 at the opposite side 55 thereof from the pin-teeth and has a guide-roller 38 on its end that is adapted to roll on the guide-rails 13 or 21 to guide the gear segment and assist in maintaining the connection 60 between the teeth of the gear seg-

ment and the driving pinion during reversing movements especially. A pair of crescent shaped reversing guides 39 and 40 are mounted on the plate 31 opposite the terminal teeth 35 of the group and are adapted to 70 engage the guide-pin 20 when the gear segment is being reversed in motion. Fig. 9 shows the plate 31 inclined in one direction and Fig. 10 shows it inclined in the opposite direction. In the operation of said oscillatory rotary gearing increased power and speed and balancing is desired to act on the driving shaft above that which may be obtained in rotating the driving shaft directly by hand, especially during the reversing operations of the agitator shaft at which periods the plate 31 is caused to change its direction of motion.

The present invention as preferably constructed comprises a wheel 41 secured to the outer end of the shaft 18 and provided with spur-teeth 41', the wheel being of suitable diameter to enable it to turn the shaft steadily, and the wheel is provided with a guard 42 that extends over the upper and side portions thereof and down substantially to the plane of the top of the cover part 5, the guard being provided with two base plates 43 and 43' that are arranged at opposite sides of the foot 15' in contact therewith and secured to the upper side of the cover part 5, the lower ends of the guard having outwardly extending aprons 44 and 44' thereon to cover upper portions of the main driving gear-wheel.

A suitable base plate 45 is provided which is suitably curved, so as to extend horizontally along the outer side of the tub 1 to which it is secured and has a long stud axle 46 and also a relatively short stud-axle 47 thereon, and on the latter is rotatably mounted a main driving gear-wheel 48 provided with spur teeth 48' that normally mesh with the spur teeth 41' of the wheel 41, the wheel 48 being provided with a crank-pin 49, so that it serves as a crank-wheel. A fulcrum 50 having a base-plate 51 is secured thereby to the outer side of the tub 1 below the base-plate 45 and has a pivot hole 52 therein, the arrangement being such that the stud axles 46 and 47 are arranged in one horizontal plane and the pivot hole 52 somewhat below and nearly in the vertical plane of the stud-axle 47, all being on the upper portion of the side of the tub. The fulcrum is provided with a pivot pin 53, and a lever 54 having a curved lower portion 55, which is provided with a jaw 56, is connected by means of the jaw and the pivot-pin to the fulcrum and so that the main part of the lever stands away somewhat from the wheel 48, the upper end of the lever being provided with a socket 57 in which is an operating handle or bar 58. The middle portion of the lever is provided with a pivot-

130

pin 59, and a connecting rod or pitman 60 has a jaw 60' on one end thereof, whereby it is connected to the pivot pin 59, the other end of the rod being connected to the crank-pin 49, the arrangement being such that the lever projects upward above the plane of the top of the tub and may be moved forward and backward with an easy swinging motion of the body of the operator without being tiresome.

10 In order to carry the crank-pin 49 over the "dead-centers" and insure steady motion, a relatively large and heavy balance-wheel 61 is mounted rotatably on the stud-axle 46 and has a relatively long hub 61 provided with spur teeth 63 that are in mesh with the teeth 48' of the main driving wheel, therefore constituting a relatively small pinion whereby the main driving gear-wheel 48 rotating at moderate speed may rotate the balance wheel at relatively high speed and, as will be seen, the wheel 41 being less in diameter than the wheel 48 is driven at somewhat higher speed relatively to the rate of movement of the operating lever, the latter being of sufficient length to provide ample power for the service required.

15 In practical use the cover part 5 is first tilted back, as shown in Fig. 2, and then the tub is partially filled with washing liquid and the articles to be washed, after which the cover part is moved down onto the top of the tub or vessel to its normal position and the teeth 41' brought into mesh with the teeth 48'. The handle 58 may then be operated by hand, so as to rotate the main driving gear-wheel 48 in either direction, and this wheel in turn will rotate the wheel 41 and the shaft 18 and also the balance-wheel 61, the shaft operating the gear segment which in turn operates the agitator shaft 22 and thereby the plate 26, all of which may be accomplished as may be seen with the minimum amount of exertion.

20 When the clothes have been rubbed sufficiently the cover part 5 may be again tilted back with little effort, so as to disconnect the wheel 41 from the wheel 48, the heavier parts of the mechanism remaining idly on the tub.

25 Having thus described the invention, what is claimed as new, is—

1. Gearing including a fixed support, a movable support, a balance-wheel mounted on the fixed support, a rotative gear-wheel on the movable support, a driving gear-wheel mounted on the fixed support and connected operatively with the balance-wheel and removably connected with the rotative gear-wheel, and means for connecting the movable support removably to the fixed support to remove the rotative gear-wheel from connection with the driving gear-wheel.

2. Machine gearing including a fixed support, a movable support hinged to the fixed

support, a driving gear-wheel and a lever mounted on the fixed support, a pitman connecting the driving gear-wheel with the lever, a balance-wheel mounted on the fixed support and having a pinion thereon in contact with the driving gear-wheel, a driving shaft rotatable on the movable support, and a gear-wheel on the driving shaft removably connected with the driving gear-wheel.

3. Machine gearing including an oscillatory prime mover, a driven shaft mounted rotatively, a balance-wheel mounted rotatively, and relatively dissimilar operating means including a vibratory device operatively connected with the prime mover and the driven shaft and also with the balance-wheel, for converting the oscillatory motion of the prime mover into continuous rotary motion and the continuous rotary motion into oscillatory-rotary motion, to move the driven shaft rotatively forward and backward alternately and farther in one direction than in the reverse direction, and to rotate the balance wheel continuously for steadyng the movements of the dissimilar operating means.

4. Machine gearing including a stationary support, a movable support hinged to the stationary support, a lever mounted on the stationary support, a toothed driving gear-wheel mounted rotatably on the stationary support and connected operatively with the lever, a balance-wheel mounted rotatably on the stationary support and operatively connected with the driving gear-wheel, a driving shaft rotative on the movable support and having a toothed gear-wheel secured thereto in contact with the driving gear-wheel and movable from said contact on movement of the movable support, and a driven shaft mounted on the movable support and operatively connected with the driving shaft.

5. In washing machine gearing, the combination of a stationary support, two stud axles and also a fulcrum mounted on the stationary support, a driving gear-wheel mounted on one of the stud axles and having a crank-pin thereon, a lever mounted on the fulcrum, a pitman connected to the lever and also to the crank-pin, a balance wheel mounted on the other one of the stud axles, a pinion on the balance-wheel and in contact with the driving gear-wheel, a movable support hinged to the stationary support, a driven shaft mounted on the movable support, a driving shaft mounted rotatively on the movable support and connected with the driven shaft, and a gear-wheel secured to the driving shaft in contact with the driving gear-wheel and removable therefrom by the movable support moving on its hinges.

6. In washing machine gearing, the combination with a stationary support, hinges secured on the support, a movable support

attached to the hinges, a driven shaft mounted on the movable support, two cones secured to the driven shaft, a gear segment loose on the driven shaft between the cones, means for connecting the gear segment with the shaft, guides for the gear segment, a main shaft mounted on the stationary support, and a pinion secured to one end of the main shaft in contact with the gear segment, of a frame base secured to the stationary support, two stud axles on the base in one horizontal plane, a driving gear-wheel rotative on one of the stud axles, a balance-wheel rotative on the other one of the stud axles, a pinion on the balance-wheel in contact with the driving gear-wheel, a crank-pin carried by the driving gear-wheel, a fulcrum mounted on

the stationary support below the plane of the stud axles, a lever mounted pivotally on the fulcrum, a pitman connected to the lever and also to the crank-pin, a gear-wheel secured to the other end of the driving shaft in contact with the driving gear-wheel, and a guard secured to the movable support and extending over said last mentioned gear-wheel and partially over the driving gear-wheel.

In testimony whereof, I affix my signature in presence of two witnesses.

HARRISON L. STALEY.
